UNITED STATES PATENT OFFICE

JAMES A. MILLICAN, OF DETROIT, MICHIGAN

PROCESS OF TREATING LEATHER AND APPARATUS THEREFOR

Application filed April 4, 1928. Serial No. 267,178.

The present invention relates to the manufacture of leather and particularly to the step in the process in which the leather is dried after the tanning process.

In the manufacture of leather, it is well known that unless steps are taken to prevent shrinkage during drying, the tanned skin will shrink greatly in area and among the objects of the present invention is the prevention of such shrinkage.

Another object is apparatus means for preventing shrinkage which shall be applicable to different sizes of skins without adjustment.

Other objects will readily occur to those skilled in the art upon reference to the following description and the accompanying drawing, in which:—

Figure 1, is a vertical section showing the apparatus for carrying out the present process and the method of its use;

Figure 2, is a fragmentary end view of the apparatus of Figure 1;

Figure 3, shows a detail of the construction and is a section on line 3—3 of Figure 1;

Figure 4, is a partial view of a modification of the apparatus, and

Figure 5, is a diagrammatic plan view showing one feature of the invention.

Figure 6 is a plan view of a modified form of the apparatus, and

Figure 7 is a sectional view thereof.

In the prior Patent No. 1,659,957, issued Feb. 21, 1928 to the present inventor, there is described and claimed a method of carrying out a process similar to the present one in which advantage is taken of the fact that atmospheric pressure on wet leather set out on a suitable surface will cause the leather to adhere closely to the surface, provided air is prevented from entering under the edges of the leather to neutralize the effect of the atmospheric pressure on the side away from the surface.

The present process is an improvement on that of the patent, in that the wet leather is held in close contact with the setting out surface throughout its area as around its edges.

In the drawing, apparatus for carrying out the process is shown to consist of the set-

ting out boards or plates 10 with pieces of leather 20 on each face thereof and intermediate members indicated as a whole by the numeral 11. These intermediate members 11 consist of frame members 12 of such size 55 as to be substantially co-extensive with the setting out boards 10, so that the boards 10 and intermediate members 11 may be stacked, one upon the other in any desired number.

The frame members 12 on their upper and 60 lower sides are provided with openings 13 through which circulation of air may be had, and between the members 12 is secured a diaphragm element 14, preferably in the form of a wire screen. Throughout the area of 65 the diaphragm 14, pegs or rods 15 will be secured which pegs or rods will be of sufficient length to extend from near one of the plates 10 to near the next plate 10 when the elements are stacked as in Figure 1. 70

Each of the pegs or rods 15 may be rounded at its ends or provided with a suitable foot, such as the soft rubber thimble indicated at 16.

The over all length of the pegs 15 should 75 be such that they will press lightly against the leather set out on the plates 10, one on top of plate 10 with the other on the bottom of the next, as shown in Figure 1. It will be understood, of course, that each plate 10 will 80 have the leather set out on each side except for the bottom and top plates of the stack.

In building up a stack of these devices, it may be found necessary to provide a spacer in order that the sagging of the central portion 85 of plates 10 may not cause too great a pressure on the leather by the ends of pegs 15.

In making the members 11, the preferred method of holding the pegs 15 in place consists in forming the pegs with a pair of beads 90 21 near their center portion and thrusting the pegs through the mesh of the wire screen until the wires of the latter lie between the beads 21, as shown in Figures 1 and 3. This will hold the pegs in place and in a position 95 at right angles to the plane of the screen.

As indicated in Figure 5, the pegs will be so placed in the member 11 that the central portion thereof will contain fewer pegs than the area around the central portion. This 100

arrangement is provided so that different size skins may be treated without the necessity for adjustment of the apparatus. The central portion of the skin will not need to be held at so many points as will the edge portions of the skins. The placing of the pegs, however, should be such that the leather will be held against the plates 10 at a large number of points throughout its area and especially near its edges.

10 Instead of using pegs 15, it is also proposed to use a corrugated fairly stiff wire screen, such as is shown at 114 in Figure 4. In this figure, the frame members 12 will be substantially identical with the frame members in Figure 1 and have similar openings 13 to permit circulation of air.

15 In the modified form of apparatus shown in Figures 6 and 7, the setting out board is shown at 10 with the leather at 20 set out thereon in the same manner as above. The holding device however is somewhat different and consists of flexible strips 30 secured at their ends in any suitable manner to cross pieces or headers 31. These strips 20 are preferably of spring material and normally bowed slightly downward as indicated in Figure 7, while the cross pieces or headers 31 will be provided with suitable means such as hooks 32 adapted to hook under the edges of board 10 to hold the device in place 25 pressing against the leather 20.

30 Strips 30 will preferably be grouped in threes as shown and each three will have a plurality of short narrow slats or strips 33 secured across them on their undersides to contact with the leather to give the desired 35 plurality of points of pressure.

35 This form of the device will of course not permit stacking but is designed to be hung by an edge.

40 Now having described the invention and the preferred form of embodiment, it is to be understood that the said invention is to be limited, not to the specific details herein 45 set forth and illustrated, but only by the scope of the claims which follow.

I claim:

1. The herein described method of treating 45 leather, which comprises setting out wet leather upon a setting out surface and applying and maintaining pressure thereon at a multiplicity of points throughout its area and maintaining said pressure during the 50 drying period.

55 2. The herein described method of treating leather which comprises setting out wet leather upon a setting out surface and maintaining said leather in close contact with said surface throughout its area during the 60 drying period.

65 3. The herein described method of treating leather, which comprises setting out wet leather upon a setting out surface and applying and maintaining pressure thereon at a 70

multiplicity of points throughout its area and maintaining said pressure during the drying period, while permitting free circulation of air to the surface of said leather.

75 4. The herein described method of treating leather which comprises setting out wet leather upon a setting out surface and maintaining said leather in close contact with said surface throughout its area during the drying period while permitting free circulation of air to the surface of said leather.

80 5. Means for drying leather comprising a setting out plate adapted to have wet leather set out thereon, a frame thereon of substantially the same dimensions as said plate, a diaphragm in said frame, and a multiplicity of pegs extending through said diaphragm and adapted each to exert light pressure on the wet leather on said setting out plate.

85 6. The herein described method of treating leather which comprises setting out wet leather upon a setting out surface and maintaining said leather in close contact with said surface throughout its area during the drying period by mechanical application of pressure.

90 7. The herein described method of treating leather which comprises setting out wet leather upon a setting out surface and applying pressure to maintain said leather in close contact with said surface throughout its area during the drying period while permitting free circulation of air to the surface of said leather.
